UNITED STATES PATENT OFFICE.

THOMAS M. PELHAM, OF NEW YORK, N. Y.

IMPROVED HOD-ELEVATOR.

Specification forming part of Letters Patent No. 95,262, dated September 28, 1869.

To all whom it may concern:

Be it known that I, THOMAS M. PELHAM, of the city, county, and State of New York, have invented a new and Improved Hod-Elevator; and I do hereby declare that the following is a full, clear, and exact description thereof, which will enable others skilled in the art to make and use the same, reference being had to the accompanying drawing forming part of this specification.

This invention relates to improvements in hod-elevating platforms, such as are used by builders for elevating and returning the hods containing bricks, mortar, and other substances, and has for its object to provide an arrangement whereby the persons who take the hod from the platform, after being elevated, may do so without requiring to step on the platform in shouldering the hod, as they must now do, as the elevators are at present constructed, by which serious accidents occur by the falling of the platform, owing to the slipping of the hoisting-gear, breaking of the ropes, and other causes.

The invention also has for its object to provide an arrangement whereby a greater number of hods may be carried up in the same space, or on platforms of equal size to others now in use.

Figure 1 represents a sectional elevation of my improved platform, and Fig. 2 represents a side elevation of the same.

Similar letters of reference indicate corresponding parts.

A are the vertical side rails, provided with slides for the guide rails, (not shown,) also with a bottom, B, an elevated bottom or platform, B', and suitable cross-rails, D, D', and E, to the latter of which the hoisting-rope is attached.

The rails D D' are intended to support the hods at the bottom of the angular parts in front of the shanks or notches F, while the lower ends of the shanks stand in sockets on the bottoms B or B', so that the tops lean against the rails, so as to carry the center of gravity so far beyond the foot-rests of the shanks as to insure the prevention of their falling away from the rest-bars D D'; also to carry the hods inward so that the out-

wardly-projecting ends will be within the line of the sides of the base of the platform.

The top and front sides of the bars D D' are inclined to suit the angles of the shanks and hods at their junction when thus leaning inward, and the recesses F are continued down the front sides of the said bars to receive the shanks.

The red lines G G', Fig. 1, represent the lines of the floor on each side of the platform, where the carriers will stand when removing the hods H, which they do by first swinging them away from the bars D, as represented in red at H', so that they will be easily and conveniently received on the shoulder while standing on the floor, and without the necessity of placing one foot on the platform, as must be done with those now in use, which are so constructed that the hods are suspended wholly by the top, in a way that prevents their swinging away from the platform. A temporary platform, G', may be placed on the floor, on the side of the elevated hods, so that the carriers may take the hods from that side as readily as from the other.

For economizing space, the bar for the hods applied at one side is elevated above the other, and, consequently, the floor B' of that side, for the support of the shanks, so that the bowl of every alternate hod may stand above the space between the two below for the shanks of the upper tiers. In this way more hods may be carried on a platform of a given size than in any other arrangement now in use.

The floor B B' of the platform is provided with ribs, I, in front of the ends of the shanks, which may have notches, L, made in them, to prevent lateral movement of the shanks at the bottom.

I propose to line the notches F in the bars with metal suitably formed, and adapted for the prevention of wear to the same.

Having thus described my invention, what I claim as new, and desire to secure by Letters Patent, is—

1. A hod-elevating platform, arranged to support the hods by the shanks at the edges on the bottom, or floor, and by leaning the under side of the top and the upper part of

the shanks against notched bars D or D', substantially as specified.

2. The arrangement of the bars D D' and the holding devices for the lower ends of the shanks of the opposite sides in the order described; that is to say, the bowls of the row on one side above those of the other, with the shanks passing between the lower ones, substantially as specified.

The above specification of my invention signed by me this 11th day of August, 1869.

THOS. M. PELHAM.
